UNITED STATES PATENT OFFICE.

WILLIAM H. RICHMAN, OF PHILADELPHIA, PENNSYLVANIA.

MACHINE FOR CUTTING PLASTIC MATERIALS.

1,221,594.

Specification of Letters Patent.

Patented Apr. 3, 1917.

Application filed June 5, 1914. Serial No. 843,238.

To all whom it may concern:

Be it known that I, WILLIAM H. RICHMAN, a citizen of the United States, residing in Philadelphia, Pennsylvania, have invented an Improved Machine for Cutting Plastic Materials, of which the following is a specification.

One object of my invention is to provide a simple and substantial machine for cutting a bar of soap or other plastic material into cakes or pieces of definite length, the apparatus being adapted to automatically operate in connection with a plodder, whereby soap is delivered in a continuous length but at a speed which is generally variable.

Another object of the invention is to provide a machine of the character indicated with novel means for supporting and maintaining its blades substantially perpendicular to the line of movement of the material acted on.

These objects and other advantageous ends I secure as hereinafter set forth, reference being had to the accompanying drawings, in which;

Figure 1 is a side elevation partially in section illustrating my invention as applied to a soap plodder;

Fig. 2 is a rear elevation on a larger scale than Fig. 1, further illustrating my machine;

Fig. 3 is a vertical section on the line *a—a*, Fig. 2; and

Fig. 4 is an elevation of one of the cutting blades and its associated parts.

As will be understood by those skilled in the soap-making art, the bar or length of soap is delivered from a plodder at a varying speed, and it is, therefore, not feasible to cut this bar into lengths by means of a cutter driven at a uniform speed, because with such a device the soap would be cut into pieces of different lengths. My machine, however, is so designed that its speed is dependent upon the speed at which the soap travels and this desired end is obtained by making the moving bar of soap serve as the operating means for said machine.

In the above drawings, 1 represents the casing of a machine for forming soap or other plastic material into continuous lengths and this is shown as including a hopper 2 leading to a cylindrical chamber 3

in which is mounted a conveying screw 4 which rotates on a substantially horizontal axis. This screw operates within the chamber 3, one of whose ends is closed by a perforated die-plate 5 confined between the casing 1 and a nozzle structure 6 whose chamber tapers from the die-plate to its outlet end.

This structure is cooled by water supplied to a water-jacket 7 and its outlet end is provided with a die-plate 8 in which is an opening 9 and which is held to the end of the nozzle structure by a clamping ring 10.

The arrangement of the above noted parts is such that the center-line of the opening 9 is preferably coincident with the axis of the screw 4 and with the center line of the chamber of the nozzle 6.

Connected to the lower front part of the die-plate 8 so as to permit of vertical adjustment relatively thereto, is a horizontally extending platform structure 11 having its edges formed with upwardly projecting flanges 12 and so mounted that its top surface is at the same level as the lower edge of the opening 9 in the die-plate. The guide-way formed by this platform and its flanged edges is preferably of slightly greater width than the width of the discharge opening 9 and said structure has projecting laterally from it an extension 13 in which is fixed a vertically extending bar 14 held in place by set-screws 15.

Carried by the upper end of the bar or standard 14 is a bearing 16 in which is radially fixed a horizontally extending shaft 17 of such length that it projects above and beyond the guideway structure 11. The outer extremity of this shaft has fixed to it a crank bar 18 between which and the bearing 16 is rotatably mounted a cutter-carrying structure formed by a hub 19 having at its ends two parallel wheel-like frames 20, preferably of such diameters that their peripheries are immediately adjacent or tangent with the top surface of the guide-way structure 11, although they are respectively 100 operative immediately outside the edges of the latter.

Mounted between the side frames 20 are a series of cutters 21 in the shape of rectangular blades having their lower edges relatively sharp and connected adjacent said

edges to journals or spindles 22 respectively operative in bearings in said two frames. One journal of each blade has fixed to it a crank arm 23 whose center-line is substantially coincident with the plane of its blade 21 and whose outer end is provided with a projecting journal 24 rotatably operative in a bearing provided by a third wheel-like frame 25. This latter is rotatably mounted 5 on a pin or journal 26 carried at the outer end of the crank arm 18 at the same distance from the center line of the shaft 17 as the distance between the center lines of the journals 22 and 24 of the blades. In the 10 present case the crank arm 18 extends vertically upward from the shaft 17 and the blades 21 are so mounted and held that they are at all times vertical. Each of the frames 20 has a number of radial series of holes 28 spaced at the same distance apart as the 15 corresponding radial holes 27.

Under conditions of operation the soap or other plastic material is delivered to the hopper 2 and the screw 4 is turned at a 20 proper speed while cooling liquid is delivered to the water-jacket 7. In the case of the machine illustrated, the soap is drawn from the hopper 2 into the chamber 3 and from there is forced by the screw 4 through 25 the die-plate 5 into the nozzle structure 6. The continuous delivery of soap into this 30 structure causes it to be strongly compressed and united into a single practically homogeneous body by the time it reaches the 35 opening 9 from which it is delivered in a relatively stiff bar of rectangular or other section which moves rearwardly, usually at a constantly varying speed, upon the table formed by the guide bracket 11. This bar 40 shortly comes into engagement with the vertical surface of one of the knives or cutters 21 and its continued rearward movement through said knife turns the knife-carrying frame on its supporting shaft 17. Obviously 45 the knife first engaged by the end of the bar has its cutting edge gradually forced toward the top surface of the table 11 until it is practically in engagement therewith when at the lowest part of its 50 path of movement. In the meantime, the next succeeding knife is gradually lowered until its cutting edge comes into engagement with the top of the bar delivered from the nozzle structure 6 and as said bar is forced 55 rearwardly upon the table the second knife is made to cut into and through it as the knife frame is turned. A definite length of material is thus cut and is forced along by the adjacent end of the plastic bar after the 60 knife has reached its lowest point and has risen clear of said bar.

Obviously, as long as there is a delivery 65 of the soap from the orifice 9, the knife frame continues to rotate and the knives are successively brought into engagement

with the bar which is thus cut into pieces all of which are of the same length. As the knife-carrying frame formed by the members 20 and the hub 19 is rotated, the eccentric frame 25 is likewise turned on the 70 crank-pin 26 and that in such manner that all of the crank arms 23 and hence all of the knives 21 are maintained in vertical planes at all points of their revolution. As a consequence of this, the knives are caused 75 to make a clean cut through the plastic material which thus forms the motive power for rotating the knife-carrying frame and operating the knives.

If it should be desired that the machine 80 cut bars of lengths different from that made with the parts arranged as shown in the drawings, then the journals 22 of the several knife blades may be placed in others of the holes 7 than the outermost ones. In 85 such a case the journals 24 of the crank arms 23 would likewise be changed into the holes 28 of the eccentric frame 25 at the same distance from the center of the pin 26 as that of the journals 22 from the shaft 90 17 and the bars of soap would then be cut into lengths depending upon the distance of said holes from the center of said shaft 17. In such case the bar or post 14 is lowered in its bearing in the arm 13 for a corresponding distance, so that the cutting edge 95 of each of the knives or blades will practically engage the surface of the table 11 as they are rotated.

Moreover, when it is desired to change 100 the section or dimensions of the bar delivered from the plodder, a die-plate 30, having an opening of the required shape is mounted between the delivery end of the nozzle structure and the plate 8 and clamped 105 in place by the member 10. By loosening the nut on the bolt 31, the platform structure 11 may be adjusted so that its top surface is on the level of the bottom of the opening in this second die-plate 30, and said 110 nut may thereafter be tightened to hold the parts in their given positions.

I claim:—

1. The combination in a machine for cutting plastic materials of a table; a rotary 115 frame mounted adjacent thereto and having a series of bearings; a second frame mounted eccentrically to the first frame; a series of flat blades having cutting edges; journals connected to said blades adjacent 120 their cutting edges respectively and operative in the bearings of the first frame; and a series of crank arms respectively connecting the blades with the second frame.

2. The combination in a machine for cutting 125 plastic materials of a supporting structure including a table; a standard; a shaft mounted in the standard; a rotary frame including two side members mounted on the shaft; plates forming knives mounted at 130

their ends in bearings provided on said side members; a crank arm on the shaft; a crank arm connected to each of the knives; and a second frame mounted on said shaft-carried 5 crank arm and connected to all of the knife crank arms.

In testimony whereof, I have signed my

name to this specification, in the presence of two subscribing witnesses.

WILLIAM H. RICHMAN.
